[57] CLAIM

I claim the ornamental design for a tooth timer, as shown and described.

DESCRIPTION

FIG. 1 is a front elevation view of a preferred embodiment of a tooth timer illustrating my ornamental design.

FIG. 2 is a left side elevation view of the tooth timer shown in FIG. 1.

FIG. 3 is a rear elevation view of the tooth timer shown in FIG. 1.

FIG. 4 is a right side elevation view of the tooth timer shown in FIG. 1.

FIG. 5 is a top plan view of the tooth timer shown in FIG. 1; and,

FIG. 6 is a bottom plan view of the tooth timer shown in FIG. 1.

The preferred embodiment of the tooth timer shown is used as a timer by twisting the top portion, or crown, of the tooth timer in a clockwise direction from the position shown in FIG. 1 to start the timer. As the timer runs, the crown portion rotates back to the position shown in FIG. 1.
